[57] **CLAIM**

The ornamental design for a handle for a vacuum cleaner or other device, as shown and described.

DESCRIPTION

A portion of this disclosure contains material to which a claim for copyright is made. The inventors or their assignee (copyright owner) have no objection to the facsimile reproduction by anyone of the patent document or the patent disclosure, as it appears in the Patent and Trademark Office files or records, but reserve all other copyright rights whatsoever.

FIG. 1 is a left-front isometric view of a handle for a vacuum cleaner or other device showing our new design;

FIG. 2 is a right elevational view thereof;

FIG. 3 is a left elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines in the figures are for illustrative purposes only and form no part of the claimed design.
